UNITED STATES PATENT OFFICE

ARTHUR M. FRAZEE, OF DULUTH, MINNESOTA

ORE DOCK

Application filed March 31, 1927. Serial No. 179,875.

This invention relates to a new and improved ore dock construction and more particularly to a movable bridge adapted for use on ore docks to facilitate the unloading of material from freight cars and the discharge of such material from the dock into vessels.

Ore docks as generally constructed, consist of a plurality of bins or hoppers over which extend railroad tracks adapted to carry the ore cars which thus dump by gravity into the hoppers. The hoppers are discharged by gravity through chutes into the vessels being loaded. In the present operation of the ore docks, the ore cars are pushed on to the dock, the brakeman at the head of the train returns to the engine at the shore end of the train which is then uncoupled and leaves the cars on the dock. The cars are of the hopper type and are so located when the train is stopped that the hoppers discharge into bins below the track. In the usual construction the hoppers are located 12 feet on centers and the cars are 24 feet on centers so that adjacent cars discharge into alternate hoppers.

The hopper cars are provided with hopper doors which are operated by a windlass form of door closing mechanism carried by the cars. After the train is spotted on the dock these doors are opened by men working on the dock and the material discharged. The material tends to stick in the cars and it is necessary to provide means for loosening the material. This is accomplished by pounding on the side of the cars or by men climbing up on the cars and using poke bars to break up the bridges formed in the material over the hopper opening. This is extremely dangerous and difficult work.

The material often spills out over the rails and on to the deck of the dock. This material must be manually shoveled off of the rails and swept from the dock into the hoppers. The hopper doors must be closed by hand before the cars can be removed. When the cars are all unloaded and the doors again raised, the engine is brought to the train and coupled on and the brakeman must then proceed to the other end of the train before

the train can be pulled from the dock. When it is desired to discharge the material from the hoppers into vessels difficulties also arise in securing a free flow of the material. It is frequently necessary for the material to be poked with long bars to break up the bridges which form over the discharge openings of the dock hoppers.

It is an object of the present invention to provide a traveling bridge carrying apparatus for opening and closing cars, for assisting in the discharge of material from cars and from dock hoppers, and for clearing the dock surfaces of surplus material.

It is an additional object to provide a construction of this character in which these various processes may be carried out by power operated apparatus with a minimum number of operators.

It is also an object to provide a construction in which the controls of the various apparatus are so interlocked as to eliminate danger to the operators.

It is an additional object to provide a bridge adapted to convey train operators from one end to the other of the train.

Other and further objects will appear as the description proceeds.

I have illustrated in the accompanying drawings a preferred embodiment of my invention, in which

Figure 1 is an end view of the bridge, parts being broken away to show the interior mechanism;

Figure 2 is a plan view showing the apparatus located in the lower portions of the bridge structure;

Figure 3 is a side elevation with parts broken away;

Figure 4 is a detailed view on an enlarged scale of the knocker construction;

Figure 5 is a detailed view on an enlarged scale showing the car trapping mechanism;

Figure 6 is a view on an enlarged scale showing a detail of one of the interlocking switches;

Figure 7 is a somewhat diagrammatic view showing a portion of the interlocking control circuits;

Figure 8 is a sectional view on an enlarged

scale showing the drive of the trapping mechanism;

Figure 9 is a vertical section taken on line 9—9 of Figure 8;

5 Figure 10 is a plan view of a lever interlock construction; and

Figure 11 is a somewhat diagrammatic perspective view of the brush controlling mechanism.

10 The ore dock deck as shown is provided with a pair of spaced railroad tracks 11 below which are located the hoppers, these latter not being shown. The rails 12 are provided to carry the bridge structure which comprises 15 the vertical legs 13 and 14 and the transverse structure 15 connecting the upper ends of the legs. At the upper end of the leg 13 are • provided the collector contact members 16 adapted to engage electric conductors to carry 20 electric power to the bridge. Each leg of the bridge is similar and only one need be described in detail.

The leg 13 as shown in Figure 3 is supported upon double flanged wheels 17 which run 25 upon the track 12. These wheels 17 are driven by motor 18 through gears 19, the counter shaft 20, gears 21 and beveled gears 22. It will be understood that motor 18 is reversible so that the bridge may be run in 30 either direction. The other leg of the bridge is provided with exactly similar driving means.

The leg 13 carries the cage 23 provided with door 24. This cage is provided for carrying the trainmen from one end to the other of the train and a suitable interlock, described in detail hereafter, is provided so that the bridge cannot be operated when the door of the cage is open.

40 The door unlocking mechanism adapted to unlock the door of the ore car is carried by the leg 13 of the bridge and is driven by the reversible motor 25 through the telescoping shaft 26 which connects to the magnetic clutch 45 27. This clutch is secured to the gear and control assembly 28, shown in detail in Figure 8, which is supported upon the legs 29, which latter are pivotally secured to the floor of the compartment located in the lower portion of the leg 13.

The assembly 28, shown in detail in Figure 8, encloses the gears and clutches for controlling and driving the mechanism for moving the assembly and also for operating the 55 trapping mechanism.

The shaft 201 is positively connected to the driven member 202 of the magnetic clutch 27, and the movable jaw clutch member 203 which is splined to the shaft, may be moved 60 to engage the clutch portion 204 which is integral with the pulley 205. The pulley 205 drives the pulley 206 on cross shaft 207 by means of belt 208 as best shown in Figure 9. The shaft 207 carries the bevel gear 209 65 which meshes with bevel gear 210 on the male

screw member 31. The jaw clutch 203 is operated by the lever 32 pivoted at 211 in the housing.

The shaft 201 carries the bevel gear 212 which meshes with the bevel gear 213 carried on shaft 214. The shaft 214 also carries the small gear 215 which meshes with the large gear 216 on counter shaft 217. The shaft 217 is also provided with the small gear 218 adapted to mesh with the sliding gear 219 carried on shaft 220. The sliding gear 219 is operated by lever 38 which moves the fork 221 engaging the groove 222. The shaft 220 carries the gear 223 through which the gear 224 is driven by means of the flexible drive member 225. The gear 224 slidably supports and drives the socket wrench 34.

The interlock shown in Figure 10 is provided to prevent simultaneous operation of the wrench 34 and the movement of the assembly 28. This interlock comprises the slide 226, guided in members 227 and movable with the lever 38. The swinging lever 228 is pivoted at 229 and is pivotally connected to slide 226 at 230. The lever 32 extends through an opening in lever 228, this opening having an arcuate portion 231 and a straight portion 232. With the parts as shown in Figure 10, either lever 32 or 38 may be operated. If lever 32 is operated it moves to the right in the straight opening 232 and when in that opening the lever 38 cannot be moved as the lever 228 cannot swing about its pivot. If the parts are in the position shown and lever 38 be moved, slide 226 moves and swings lever 228 to bring lever 32 into the arcuate portion 231 of the opening and that lever then cannot be moved.

The apparatus in the compartment in the lower portion of the leg is completely enclosed by a netting or grill work through which extends a sliding door 30. This door operates a control switch which will be described in detail hereafter. When the door is opened the car door operating mechanism 105 may be swung downwardly to the dotted line position of Figure 5. This downward movement is accomplished by rotating the male screw member 31 by means of the train of gears connected to the magnetic clutch 27 by means of the jaw clutch 203, controlled by lever 32. Rotation of the screw 31 causes it to pass into the lower member or female screw 33 which draws the assembly 28 to the dotted line position of Figure 5. When the assembly reaches the desired lower position the lever 32 is operated to disengage the jaw clutch which it controls and the assembly remains held in the desired position.

The mechanism carrying the socket wrench 34 extends laterally from the assembly 28, as viewed in Figure 5, and is pivoted to the assembly so as to be movable in a vertical arc about the shaft 220 at its point of connection. This movement is accomplished by means of 125

the handle 35 which drives a gear meshing with the rack 36. As best shown in Figure 2, the socket wrench 34 is provided with a hand wheel 37 by means of which the wrench may 5 be moved inwardly and outwardly. The wrench is driven in either direction by power supplied from the reversible motor 25 through the magnetic clutch 27 and the gear train in assembly 28, controlled by the clutch 10 lever 38. The magnetic clutch 27 is controlled by pressure on the foot button 93.

The knocker assembly is shown in detail in Figure 4 and comprises electrically driven apparatus enclosed in the housing 39 adapted 15 to reciprocate the hammer head 40. The housing 39 is supported by the parallel members 41 and 42, the upper ends of which are connected to the slide 43 operating on the vertical guides 44. The counterweights 45 are 20 connected to the slide by cables 46 passing over pulleys 47. The hand wheel 48 is carried by the slide 43. This hand wheel 48, by means of the planetary gears 49, drives the shaft 50 which carries the upper ends of the 25 parallel members 41 and 42. The hand wheel 48 thus serves to swing the hammer 40 against a car or to withdraw it from contact with the car. The parallel member 42 is formed in two sections which may be extended or 30 drawn together by means of the hand wheel 51 which rotates the threaded sleeve 52 by means of the beveled gears 53 and 54. Rotation of this hand wheel 51, therefore, serves to tilt the hammer housing 39 up or down. The 35 entire assembly may be raised or lowered by raising or lowering the slide 43.

The leg 13 of the bridge also carries the shovel member 55, best shown in Figures 2 and 3. This shovel member is carried by one 40 end of the parallel members 56 and 57. Member 57 has its opposite ends secured to the short vertical shaft 58 located below the floor of the compartment. Member 56 has its opposite end pin connected to the bridge which 45 connection acts as a hinge for the parallel motion mechanism. Shaft 58 also is provided with the operating arm 59 which latter is connected by the operating rod 60 to the stud 61 carried by the disk crank 62. The disk crank 62 carries electric contacts which 50 will be described more in detail hereafter. The disk crank 62 is driven by motor 63 through the beveled gears 64. The inner end of the parallel member 57 is provided with 55 the roller 65 which rolls on track 66. This track may vary in height so that the shovel 55 is raised from contact with the deck of the dock when it is withdrawn to the traveling position in which it is shown in Figures 60 2 and 3.

The cab 67 is supported upon wheels 68 rolling on rails 69 carried by the transverse structure 15 of the bridge. The cab is moved back and forth across the bridge as desired 65 by power supplied by motor 70 shown in

Figure 1, to the pulley 94 of Figure 3, over which passes a cable connected to the opposite sides of the bridge. The cab carries the poke bar 71 which has the cables 72 and 72' connected to its upper and lower ends. These 70 cables 72 and 72' are attached to the large pulley 95 shown in broken lines in Figure 3, this pulley being driven by motor 73 through gears 96, shaft 97, clutch 98 and bevel gears 99. The poke bar 71 is guided by rollers 100. 75

The cab also carries on its upper portion the chains 74 composed of heavy pointed links. These chains are carried by cables 75 passing over drums 76. These drums are operated by motors 77 so that the heavy 80 chains may be raised or lowered into the mass of material in the cars or in pockets of the dock to break up bridges which form in the material.

The cab further carries the rotating brush 78 which is driven by means of motor 79 through gears 80, 81 and 82. The brush gears and motor are carried in a frame 83 supported by a pair of cables extending around the drums 84 and 85. These drums are carried by shaft 86 which is driven by means of the motor 87. The shaft 86 also carries the drum 88 upon which is wound the conductor cable 89 leading to the motor 79, the shaft and drums being supported in frame 90. The 90 sliding rods 91, best shown in Figure 11, are moved in opposite directions by lever 92. Lever 92 rotates a worm 233 meshing with a worm gear 234 on cross shaft 235. The cross shaft 235 carries at its opposite ends the gears 236 and 237 meshing with the rack gears 238 on the rods 91. It will be noted that gear 236 is below its rack while gear 237 is above its rack so that rotation of shaft 235 moves the two rods 91 in opposite directions. 95

The rods 91 are slidably supported in fixed bearings 239. The torsion springs 240 have one end of each secured to a bearing 239 and its opposite end secured to a collar 241 splined on to the rod 91 so as to be slidable thereon but to rotate therewith. The springs normally hold the rods 91 in such position that the forks 242 are horizontal as shown in full lines in Figure 11. When the frame 83 is raised to the dotted line position the forks 242 are swung upwardly against the resistance of springs 240. Translation of the brush in the horizontal plane is accomplished by movement of the entire bridge, by movement of the cab, or by a combination of both said movements. 105

The control lever 101 controls the circuits to the motors for moving the bridge and also the circuit to the motor for moving the cab back and forth on the bridge. 115

A typical solenoid switch of the type used in the interlocking controls is shown in Figure 6. The member 102 is directly connected to the element controlled, as for example, the cage in the leg of the bridge. This mem- 120

ber is provided with the perforation 103 into which is fitted the plunger 104 extending from the switch. The plunger 104 carries the lower contact 105 and the upper contacts 106. The plunger is normally held in the position shown by the spring 107; the plunger thus enters the perforation 103, holding the cage door shut, for example. The solenoid coil 108 is connected by wires 109 and 110 with a push button in the cab. With the switch in the position shown the circuit is closed through wires 111 and 112 by the contact 105. This is the main circuit giving the operator in the bridge cab control over movement of the bridge. When the push button in the cab is depressed, the solenoid coil 108 is energized and the plunger 104 drawn upwardly, breaking the circuit through wires 111 and 112 and making a circuit through wires 113 and 114 by means of contact 106. This may be, for example, the circuit to the hammer operating mechanism. The operator in the lower cage moves the hammer from its rest position, thus moving the member 102 so that the perforation 103 is no longer in registration with the plunger 104 and this plunger engages the face of the plate 102 and is maintained in its upper position, closing the circuit through wires 113 and 114, even though the cab operator removes pressure from the control button and the solenoid becomes deenergized. When the use of the hammer mechanism is completed, it is restored to rest position, the perforation 103 again brought in registration with the plunger 104 which is forced down by spring 107, breaking the circuit through wires 113 and 114 and closing the circuit through wires 111 and 112, thus restoring control of the bridge to the cab operator.

A general outline of typical control circuits for the control of the bridge is shown in Figure 7, only a portion of the lines being shown in detail for the sake of clearness since the other lines are similar.

The control for the main bridge drive circuit comes in through terminal 115 and passes through wire 116 to the interlock controlled by the door to the right-hand lower cage at 117, the interlock on the right-hand shovel at 118, the interlock on the right-hand hammer at 119, and the interlock on the right-hand trainman's cage at 120. The wire 121 then leads to the interlock 122 on the left-hand trainman's cage, the left-hand hammer interlock at 123, the left-hand shovel interlock at 124, and the left-hand cage door interlock at 125. From the interlock 125, the wire 126 leads to the terminals 127 and 128. The wire 129 leads from terminals 130 to wire 131 which connects at 132 to the starting coil for propelling the left-hand side of the bridge backward and at 133 to the starting coil for propelling the right-hand side of the bridge backward. The wire

134 leads from terminal 135 to the wire 136 which connects to the starting coil 137 for propelling the left-hand side of the bridge forward and the starting coil 138 for propelling the right-hand side of the bridge forward. All four starting coils are connected by wire 139 to wire 140 which leads to the other terminal 141 of the main bridge drive circuit.

The controller handle 142 may be moved to connect either terminals 128 and 135 to propel both sides of the bridge forward or to connect terminals 127 and 130 to propel both sides of the bridge backward. However, such movement of the lever will not move the bridge if the circuit is broken at any one of the eight interlocks.

The left-hand interlock solenoid circuit leads from terminal 143 by wire 144 to the trainman's cage button 145, the lower cage door button 146, the hammer button 147, and the shovel motor button 148. From button 145 the wire 149 leads to the solenoid coil in the trainman's cage interlock 122 and from this solenoid the wires 150, 151 and 152 lead to the terminal 153.

From button 146, the wire 154 leads to the solenoid on the left cage door interlock 125. From the solenoid the circuit returns to terminal 153 by wires 155 and 152. From button 147 the wire 156 leads to the solenoid in the hammer interlock 123 and the return is through wires 157, 151 and 152 to the terminal 153.

The control for starting the shovel has a circuit leading from button 148 through wire 158 to starting coil 161. The holding circuit leads from wire 144 through wire 244 to a contact at 159 on the rim of the disk crank 62, then through wire 160 to the starting coil of the shovel motor indicated at 161. From the coil 161 the return is through wires 162, 151 and 152 to the terminal 153. The contact 159 on the disk crank covers about three hundred and fifty degrees of the circumference of the disk crank so that the circuit to the starting coil when closed initially by button 148 long enough to cause movement enough to cause the fingers to engage the contact 159, will continue closed after the button 148 is released until the fingers come to the ten degree blank space on the crank rim. The contact 124 closing the main bridge drive circuit covers an arc of about ten degrees so that the bridge may be moved when the shovel is at rest but may not be moved when the shovel is operating.

The operation of the trainman's cab door interlock is similar to the typical one previously described. Pressure on the button 145 energizes the solenoid in interlock 122, the plunger is withdrawn from the perforation 163 in bar 164 and the door 165 may be opened. The main bridge circuit is thus interrupted. When the door 165 is again

closed the plunger of the interlock enters the perforation 163 and the main bridge circuit is closed.

The hammer interlock 123 is also similar in operation, and pressure on button 147 closes the solenoid circuit, drawing upwardly the plunger out of perforation 166 in the rod 167. The upward movement of the plunger also closes the hammer operating circuit through wires 168 and 169. A mechanical lock for maintaining the hammer in the rest position is connected to the rod 167. The lock comprises a fixed member 170 having an angular slot 171 to receive a stud 172 on the hammer. The rotating member 173 is pivoted to the fixed member 170 at 174 and is provided with a slot 175 also adapted to receive the stud 172. The arm 176 is rigidly secured to the member 173 and is connected by link 177 to the rod 167. In Figure 7 the parts are shown in the unlocked position in full lines and the stud 172 may pass out of both slots.

In restoring the hammer to the locked rest position it is brought to such position that the stud 172 enters both slots 171 and 175 as shown in full lines in Figure 7, and is then moved to the left, the stud 172 being guided by slot 171, and due to its engagement also in slot 175, it rotates the member 173 about its pivot 174 to the dotted line position of Figure 7. This movement of member 173 is communicated to rod 167 by arm 176 and link 177 and brings the perforation 166 into registration with the plunger in the interlock 123 so that the plunger drops down and locks the rod. This serves, by means of stud 172, to lock the hammer in the rest position.

The interlock 125 on the lower cage is operated by pressure on button 146 which raises the plunger, opening the main bridge circuit and closing a circuit through wires 178 and 179. These wires are in a signal light circuit which is closed to light an indicating light in the upper cab when the door is opened.

A second control 180 is provided on the cage door operating in connection with the same slide 181 as the interlock 125, this slide moving with the cage door. The slide 181 is provided with the perforation 182 coacting with the plunger in the interlock 125 and also with the perforation 183 coacting with the plunger 184 in the control 180. This perforation 183 is provided with a sloping slide so that when the plunger 184 is in the perforation, the slide may be moved and will force the plunger out. There is no solenoid in the control 180. When the door is fully opened and the plunger 184 is in perforation 183, a circuit is closed through wires 185 and 186 and the car trapping mechanism may be put in operation by current flowing through these wires.

When the door is closed or in an intermediate position, the plunger 184 is in its upper position and closes a circuit through wires 187 and 188 which circuit includes a signal light in the upper cab. It will, therefore, be apparent that when the cage door is closed, the light in circuit 187 and 188 is lighted, when it is open the light in circuit 178 and 179 is lighted and when in an intermediate position both signal lights are lighted so that the cab operator is constantly advised as to the position of the door.

It will be understood that the right-hand side of the bridge is provided with controls similar to those described, their circuits not being shown in detail but merely indicated at 189 and 190.

I claim:

1. Ore dock mechanism comprising apparatus adapted to travel on said dock, an operator's cage carried by said apparatus and a fixed cage for carrying a trainman carried by the lower portion of said apparatus.

2. Ore dock mechanism comprising apparatus adapted to travel on said dock upon opposite sides of a car on the dock, an operator's cage carried by said apparatus, an electric drive for causing the travel of said apparatus, a cage for carrying a trainman carried by said apparatus, a door for said cage, and an interlock operated by the cage door located in the power circuit whereby the circuit is broken when the door is open.

3. Ore dock mechanism comprising apparatus adapted to travel on said dock, portions of the apparatus being located on opposite sides of cars on the dock, mechanism carried by said portions adapted to engage cars to open the doors thereof, and mechanism carried by said portion adapted to hammer car sides to aid in the discharge of material therefrom.

4. Ore dock mechanism comprising apparatus adapted to travel on said dock, portions of the apparatus being located on opposite sides of cars on the dock, power driven mechanism carried by said portions for hammering car sides to facilitate the discharge of material therefrom, a power circuit for causing the travel of the apparatus, and an interlock whereby the apparatus travel circuit is broken when the car hammering mechanism is in use.

5. The combination with a dock containing a plurality of cargo bins and having a train of cargo cars mounted thereon adapted to extend over said bins, of a support adapted to extend over said cars successively, a plurality of devices carried by said support for facilitating the movement of the cargo from said train to said bins, automatic interlocking means for preventing the operation of any of said devices contemporaneously with the operation of another of them, and automatic interlocking means for preventing the

movement of said support contemporaneously with the operation of some of said devices.

6. The combination with a dock containing a cargo bin and having a cargo carrier standing over said bin, of a support mounted upon said dock and partly extending over carrier, means mounted upon said support for facilitating the transfer of the cargo of said carrier to said bin, and automatic interlocking means for preventing the operation of a part of said facilitating means contemporaneously with another part thereof.

7. Ore dock mechanism comprising apparatus adapted to travel on said dock, portions of the apparatus being located on opposite sides of cars on the dock, means carried by the lower portions of the apparatus adapted to engage cars to open the doors thereof, said means comprising a pivotally mounted mechanism provided with a rotatable socket wrench, and power means for driving said socket wrench, and other means carried by said apparatus adapted to hammer car sides to aid in the discharge of material therefrom.

8. Ore dock mechanism comprising apparatus adapted to travel on said dock upon opposite sides of a car on the dock, a portion of the apparatus extending above the car, an operator's cab carried by said portion of the apparatus, and means for hammering car sides carried by a lower portion of the apparatus, said means comprising vertical guides, supporting members vertically adjustable on said guides, and an electrically operated hammer secured to said supporting members.

Signed at Duluth, Minnesota, this 21st day of March, 1927.
